UNITED STATES PATENT OFFICE.

ALBERT H. HAVARD, OF URBANA, ILLINOIS.

DESIGN FOR A CONCRETE GRAVE-LOT MARKER.

46,817.

Specification for Design.

Patented Jan. 5, 1915.

Application filed October 27, 1913. Serial No. 797,691. Term of patent 7 years.

To all whom it may concern:

Be it known that I, ALBERT H. HAVARD, a citizen of the United States, residing at Urbana, in the county of Champaign and State of Illinois, have invented a new, original, and ornamental Design for Concrete Grave-Lot Markers, of which the following is a specification, reference being had to the accompanying drawing, forming part thereof.

The figure is a perspective view of a con-

crete grave lot marker showing my new design.

I claim:

The ornamental design for a concrete grave lot marker, as shown.

ALBERT H. HAVARD.
